ATTORNEYS

UNITED STATES PATENT OFFICE

BERNHARD HOETGER, OF WORPSWEDE, NEAR BREMEN, GERMANY

TRAVELING SIGNBOARD

Application filed March 15, 1929, Serial No. 347,249, and in Germany March 30, 1928.

In the devices which are used to produce constantly or intermittently traveling or changing signs the disadvantage prevails, that the moving sign bands or aprons to which the sign bands or announcements are applied are subjected to excessive strains and, consequently, premature wear. This is especially the case when plastic signs or representations are used, and it is the main object of the invention, to remove these drawbacks by largely reducing the friction between the aprons and their guiding members.

According to the invention the sliding friction which prevails in the hitherto known devices is transformed into rolling friction by causing all the apron guiding rollers to move with the aprons at the same, or approximately the same speed.

In those cases in which the aprons are passed over stationary members, the advantages of reduced friction which are offered by the invention, may however, also be obtained by the employment of special guide or transport rollers in connection with such stationary members and over which the aprons are adapted to move.

These and other objects of the invention will be apparent from the accompanying drawings in which two embodiments of the invention are illustrated by way of example.

In these drawings

Fig. 1 is a front elevation of the device.

Fig. 2 is a section on line II—II and

Fig. 3 is a section on line III—III of

Fig. 1.

Fig. 4 shows a modified form of the invention in top plan.

Fig. 4^a is a fragmentary front elevation, partly broken away, of the form of the invention shown in Fig. 4.

Fig. 5 represents a detail, showing part of the driving means for the rollers.

Fig. 6 is a sectional plan view on the line VI—VI of Fig. 5.

The aprons *b* which collectively represent the advertising or other sign producing surface are adapted to move over the rollers *c*, there being two of such rollers provided for each apron although, of course, any greater number or other arrangement may be pro-

vided. The said rollers *c* and, therewith the aprons *b*, are driven by means of a belt or chain *e* which receives its motion from a gear wheel *f* supported in a bracket *g* and rotated either by a hand crank, as indicated by the broken lines in Fig. 1, or preferably by an electric motor *h*. The belt or chain *e* is caused to move over and mesh with chain wheels *l* on the lower trunnions *m* of the rollers *c'* which are positioned at the corners of the assembly. In order to transfer the movement of the rollers *c'* to the other rollers *c*, all of the said rollers are provided with pinions *o* meshing in succession one with the other.

In the arrangement shown in Fig. 4 flat boards or slats *i* are shown to be used, which present a broader advertising surface for each of the aprons *b*. These boards or slats remain stationary while the aprons move over same, and according to the invention guide rollers *k* are journaled at the ends of the said slats and may be driven in a manner similar to the one just described by a belt or chain from a driving gear such as *f* in Fig. 1, and over which the aprons *b* are guided. Instead of driving the rollers *k* and leading the aprons thereover, the said aprons may be driven in any other suitable manner and the rollers *k* simply used as idlers to reduce friction.

Apart from the purpose of advertising, the arrangement of moving sign bands or aprons, according to the invention, may be used as a blackboard with changing writing surface, such as may be employed for school or demonstration purposes. In this case the aprons *b* are simply made black in color, and it will be evident that owing to the very large total writing surface it is possible to write or draw a large number of different texts or representations upon the surface, without being obliged to wipe out the previous writings in case they should be desired to be shown again.

What I claim is:—

A sign board comprising a plurality of traveling aprons, a pair of front rollers for each apron, said rollers being arranged in co-planar relation whereby a composite dis-

play surface is presented by said aprons, similarly arranged pairs of rear rollers for said aprons whereby a rear display surface is presented, a flexible driving element for rotating said rollers, and a stationary plate connecting the rollers of each pair and forming a backing for the visible portions of the aprons.

In testimony whereof I affix my signature.
10 BERNHARD HOETGER.
